(57) **CLAIM**

We claim the ornamental designs for a luminaire, as shown
and described.

DESCRIPTION

FIG. 1 is a perspective view showing our new design for a
luminaire;

FIG. 2 is a right side view of the luminaire of FIG. 1, the left
side view is a mirror image of the right side view;

FIG. 3 is a top view of the luminaire of FIG. 1;

FIG. 4 is a bottom view of the luminaire of FIG. 1;

FIG. 5 is a front view of the luminaire of FIG. 1; and,
FIG. 6 is a back view of the luminaire of FIG. 1.

The appearance of any portion of the article between the
break lines forms no part of the claimed design.

The portions shown in broken lines are not part of the
claimed design but show the environment in which the
design is associated.

1 Claim, 5 Drawing Sheets
